UNITED STATES PATENT OFFICE.

GEORGE A. MARVIN, OF SENECA, KANSAS.

CALF-WEANER.

SPECIFICATION forming part of Letters Patent No. 280,642, dated July 3, 1883.

Application filed April 21, 1883. (No model.)

To all whom it may concern:

Be it known that I, GEORGE A. MARVIN, a citizen of the United States, residing at Sene-
5 ca, in the county of Nemaha and State of Kan-
sas, have invented certain new and useful Im-
provements in Calf-Weaners; and I do declare
the following to be a full, clear, and exact de-
scription of the invention, such as will enable
others skilled in the art to which it appertains
10 to make and use the same, reference being had
to the accompanying drawings, and to letters
or figures of reference marked thereon, which
form a part of this specification.

Figures 1 and 2 are perspective views of my
15 calf-weaner.

This invention has relation to devices for
weaning calves; and it consists in the construc-
tion and novel arrangement of the two-branch
20 spring nozzle-piece, having lateral inward pro-
jections for the nostrils, and, in connection
therewith, a transverse fastening hook-bar or
hook-bars, the nozzle-piece and hook-bar, or
either of them, being provided with pointed
25 prongs, all as hereinafter set forth.

The device is usually constructed of wire.
In the accompanying drawings, the letter *a*
designates the two-branch nozzle-piece, formed
with a rounded bend, *b*, or bridge, which passes
over the nose, its arms or branches *c c* being
30 bent inward to form the projections *d d*, which
are inserted into the nostrils from each side.
The ends of the branches are bent in loop form
to provide eye-connections at *e e*, and extend
beyond said eye-connections in the form of
35 prongs *g g*. A transverse hook-bar, *h*, is con-
nected to one of the eyes *e* by means of a loop-
bend, *k*, and is provided near its other end

with a hook-bend, *l*, to engage the other eye
e of the nozzle-piece *a* when the branches of
the latter are sprung toward each other. The 40
ends of the hook-bar are provided with lat-
erally-projecting prongs *m*. A second hook-
bar, as indicated at *v*, may be employed in
place of the hook-bar *h*, or in addition there-
to. The hook-bar *v* is provided with for-
wardly-projecting prongs *z*. When the hook-
bar is unfastened from the spring nozzle-piece,
the elasticity of the latter causes its branches
c c to spring outward, or away from each other
a little, so that the device can be easily re- 50
moved from the nose of the calf.

When the device is to be attached to the ani-
mal, the projections *d d* are inserted into the
nostrils, and the branches *c c* are brought to-
ward each other to clamp the septum between 55
the nostrils sufficiently to prevent disengage-
ment, and the hook-bar having been engaged,
the fastening is made secure.

Having described this invention, what I
claim, and desire to secure by Letters Patent, 60
is—

A calf-weaning device consisting of a two-
branch nozzle-piece having lateral inward pro-
jections for the nostrils, all formed from a sin-
gle piece of spring-wire, and a transverse fast- 65
ening hook bar or bars provided with prongs,
and hooks and eyes to connect with the noz-
zle-piece, substantially as specified.

In testimony whereof I affix my signature in
presence of two witnesses.

GEORGE A. MARVIN.
